Attorney

UNITED STATES PATENT OFFICE

JOHN ANDREWS, JR., OF KERROBERT, SASKATCHEWAN, CANADA

COMBINED RAIL LIFTER AND SPIKE PULLER

Application filed September 25, 1929. Serial No. 395,132.

The invention relates to implements for use by railway track men to lift the rails relatively to the tie for insertion of plates between the rail base and the tie.

5 Heretofore this work has been done by means of crow bars or pinch bars, but because of the length of time it requires with such implements to accomplish the work, and because of the fact that men are daily injured in 10 such work, the invention of the application has been developed to make it possible for two men to accomplish what has heretofore required four or more men, and to make it possible for the two men to accomplish work of 15 several groups of men, and also eliminate hazards to the men in the operation.

A further object of the invention is the provision of a tool of the character stated comprising a handle with a downturned end 20 to which is secured a U-shaped member having its bent portions spaced a considerable distance from one another and from the handle and provided with shoulders to engage under the base of the rail, the portion of the 25 U-shaped member adjacent to the handle forming the fulcrum for a lever to raise the rail relatively to the tie, the spaced ends of the U-shaped member providing for insertion of a plate under the rail for leveling the track 30 and also to relieve the tie of the wear incident to the rails resting directly on the tie. The tool also has the end of the handle remote from the U-shaped member provided with a claw that may be used for drawing 35 spikes.

The invention will be described in detail hereinafter and will be found illustrated in the accompanying drawings in which

40 Figure 1 is a top plan view of a fragment of a railroad track showing the improved tool in operative position,

Figure 2 is a side view of the tool showing the track in cross section,

45 Figure 3 is a sectional detail view on a plane indicated by the line 3-3 of Figure 1, and

Figure 4 is another detail sectional view on a plane indicated by the line 4-4 of Figure 1.

50 In the drawings similar reference charac-

ters are used to designate corresponding parts throughout the several views.

The improved tool comprises a handle 1 having one of its ends provided with a claw 2 that may be used for withdrawing railway spikes, and the like, while its other end has a downturned portion 3 to which is secured a U-shaped member 4 made of a plate of metal, such for instance as steel and having its arms 5 spaced remote from one another and from the downturned end 3 so as to provide means for engaging under the base of a rail A remote from a tie B on which the member 4 is rested and forms a fulcrum for the tool in lifting the rail A for the purpose of inserting a plate 65 under the rail and above the tie. The U-shaped member is widened at each side of the middle portion of the bight thereof as shown at 6, and has the arms 5 provided with a considerably widened portion including a downwardly extended portion 7 to add to the strength of the device. The extremities of the U-shaped member 4 are provided with cutaway portions forming shoulders 8 that extend under the base of the rail A a sufficient 70 distance to insure raising the rail off the tie when in operation. 9 indicates a brace member secured as shown at 10 to the handle 1 and having a downturned portion 11 that is secured with the downturned portion 3 to the U-shaped member 4 by means of a bolt or other suitable fastening 12. 13 indicates 75 spacing sleeves mounted between the handle 1 and the brace member 9 and held secured thereto by means of bolts 14 secured to said handle 1 and brace member 9 and extending 80 through the bore of said sleeves.

What is claimed is:—

1. A tool of the class described, comprising 90 a handle having a downturned end, a U-shaped member secured to said down-turned end and adapted to rest on a railroad tie, a brace secured to said handle and to said member, spacing means secured between said handle and brace, and the ends of said member provided with shoulders adapted to engage under the base of a railroad rail to lift the rail relatively to the tie.

2. A tool of the class described, comprising 100 a handle having a downturned end, a U-

shaped member secured to said down-turned end, a brace secured to said handle and to said member, a spacing sleeve, a bolt secured to the handle and brace and inserted through
5 the sleeve, and the ends of said U-shaped member provided with shoulders, said U-shaped member adjacent to the handle being adapted to rest on a railroad tie and provide a fulcrum for the tool, and the shoulders being
10 adapted to engage under the base of a railroad rail to lift it relatively to the tie.

In testimony whereof I affix my signature
JOHN ANDREWS, Jr.
